Primary Examiner — Rachel Steitz*Assistant Examiner* — Jennifer Gill(74) *Attorney, Agent, or Firm* — Miskin & Tsui-Yip, LLP; Gloria Tsui-Yip(57) **ABSTRACT**

A compact, modular, cosmetic organizer that provides portability and ease of use and access to the cosmetics. The cosmetic organizer includes a housing, a tray, a plurality of foldable modular boxes, and a foldable mirror. The modular boxes and mirror are collapsible for storage within the housing. When in use, the modular boxes rest within the tray to allow easy access to the cosmetics.

COMPACT ORGANIZER FOR COSMETICS

This application claims the benefit of provisional patent application Ser. No. 61/793,672, filed on Mar. 15, 2013, which is hereby incorporated by reference

FIELD OF THE INVENTION

The invention relates to a cosmetic organizer. In particular, a compact, modular, cosmetic organizer that provides portability and ease of use and access to the cosmetics.

BACKGROUND OF THE INVENTION

Cosmetic organizers that are compact and portable are common. An example of such prior art cosmetic organizers includes a small pouch with sleeves and/or zippered pockets. Each sleeve or pocket is designed to hold a particular type of cosmetics. As there are twenty-eight (28) basic cosmetic categories of cosmetics, each having its own specific shape and size, such cosmetic organizer disadvantageously cannot store and keep all the categories of cosmetics organized. Further, when a user seeks to access the cosmetics from such a cosmetic organizer, a user must zip and unzip pockets, slide an item from and into a sleeve, etc., which is not convenient and time consuming. Often, a cosmetic item may be lost towards the bottom of a pocket or inside the pouch.

Other prior art cosmetic organizers that allow easy access of cosmetics and provide storage for all basic cosmetic categories are disadvantageously not compact. An example of such cosmetic organizer is the inventor's U.S. Pat. No. 7,591,382, which is hereby incorporated in its entirety by reference.

Therefore, there is a need for a cosmetic organizer that is compact, modular, portable and yet allows ease of access to the cosmetics when in use.

SUMMARY OF THE INVENTION

The present invention is a cosmetic organizer that is compact, modular, portable and provides ease of access to the cosmetic when in use.

The cosmetic organizer of the present invention comprises a housing, a tray, a plurality of modular boxes, and a mirror. The modular boxes and mirror are collapsible such that they can be stored within the housing, either in the tray or in compartments of the housing.

Cosmetics may be stored in the different compartments of the housing or in additional pouches or bags that may be stored in the tray and within the housing.

BRIEF DESCRIPTION OF THE DRAWINGS

Preferred embodiments of the present invention have been chosen for purposes of illustration and description and are shown in the accompanying drawings forming a part of the specification wherein:

FIG. 1 is the housing of the cosmetic organizer of the present invention in a closed position.

FIG. 2 is the housing of the cosmetic organizer of the present invention in an open position.

FIG. 3 is the removable tray of the cosmetic organizer.

FIGS. 4A-4I are various modular boxes for use with the removable tray of the cosmetic organizer.

FIG. 5 is a bottom perspective view of the modular box shown in FIG. 4A.

FIG. 6 illustrates one embodiment of a collapsible modular box of FIG. 4A.

2

FIG. 7 illustrates another embodiment of a collapsible modular box of FIG. 4A.

FIG. 8 shows the present invention when in use, with the removable tray and two modular boxes.

FIG. 9 is a collapsible mirror for use with the cosmetic organizer.

FIG. 10 shows a planar sheet with a grid of indents.

FIGS. 11A-11C show various shapes of the housing and the tray.

FIG. 12 illustrates another embodiment of a collapsible modular box of FIG. 4A.

FIG. 13 illustrates panels of another embodiment of a collapsible modular box of FIG. 4A.

FIG. 14 is another embodiment of a collapsible mirror for use with the cosmetic organizer.

DETAILED DESCRIPTION OF THE PREFERRED EMBODIMENTS

With reference to the drawings, wherein the same reference number indicates the same element throughout, there is shown in FIG. 1 the cosmetic organizer 100 of the present invention in a closed position. As shown in FIGS. 1-4, the cosmetic organizer 100 includes a housing 10, a tray 30, and at least one modular box 50. The tray 30 and modular box 50 are stored within the housing 10 to facilitate portability of the cosmetic organizer 100.

As shown in FIGS. 1 and 2, the housing 10 has a rectangular shape, with a base 11 and a cover 12 connected to each other on one side and by a zipper 13 along the remaining three sides of the housing 10. The base 11 defines the main storage compartment 14. On the outer surface of the cover 12 is an additional compartment 15 having a zipper 16. On the inner surface of the cover 12 are additional compartments 17a, 17b, etc., which may be sleeves for slidably receiving cosmetic item(s). Each of the compartments 14, 15, 17a, 17b, etc. of the housing 10 can be closeable with a zipper, Velcro® attachments, snap buttons, or other closure means known to one skilled in the art. The compartments 14, 15, 17a, 17b can be used to store various cosmetic items when cosmetic organizer 100 is closed and not in use. More or less compartments can be provided on both the inner and outer surfaces of the cover 12 or along the inside edges of base 11. Although zipper 13 is shown to be along three sides of the housing 10, it can also be on only one side of the housing 10 with the remaining three sides connected such that the housing 10 acts as a sleeve or it can be on all sides of the housing 10 such that the cover 12 can be completely removed from base 11. The housing 10 is preferably made of a soft material, such as silicone, neoprene, textile, rubber, etc. However, housing 10 can also be made of a hard material such as metal, carbon fiber, plastic, etc.

As shown in FIG. 3, the tray 30 has a planar portion 31 with four walls 32a, 32b, 32c, 32d extending upwardly from the perimeter of the planar portion 31, defining an internal area 33 surrounded by an edge 34. A handle element 37 may be provided on one or more of the four walls 32a, 32b, 32c, and 32d. Handle element 37 may be an opening on two or more walls 32a, 32b, 32c, and 32d. Handle element 37 may also be a rolled lip extension 38 on two or more walls 32a, 32b, 32c, and 32d. The handle element 37 or 38 may extend across either a portion of or along the entire width of the walls 32a, 32b, 32c, and 32d. Within the internal area 33 of the planar portion 31 is a grid of indents 35 that are evenly spaced apart from each other. Similar to the housing 10, tray 30 may be made of a soft or hard material, as long as it provides a certain degree of sturdiness to serve the purposes to be described below. Each indent 35 may be hemispherical, a cylindrical

cavity, or any other shape and can be of different sizes. Indent 35 may also be a through aperture. Instead of having a grid of indents 35 on the planar portion 31 that is integral with the tray 30, a grid of indents 35 may be on a separate, removable, planar sheet of material 36 (as shown in FIG. 10) that can be placed on top of the planar portion 31 within the internal area 33. Tray 30 is stored in the main storage compartment 14 of the housing 10 when the cosmetic organizer 100 is closed and not in use. Tray 30 may also rest in the main storage compartment 14 of the housing 10 when the cosmetic organizer 100 is in an open position and being used (tray 30 of FIG. 8 when in use can be placed within compartment 14 of FIG. 2).

As shown in FIGS. 4A-4I, each modular box 50 has a support base 51 with four panels 52a, 52b, 52c, 52d extending upwardly from the first side of the support base 51 defining a storage area 53. As shown in FIG. 5, at the second side of the support base 51 are four protrusions 55. Each protrusion 55 is shaped to generally correspond to the shape of the indent 35 and it may be hemispherical, cylindrical, or any other shape. The spacing of the protrusion 55 corresponds to the grid of indents 35 on the planar portion 31 of the tray 30 such that each modular box 50 sits securely in a defined position within the internal area 33 of tray 30 within the edge 34 as shown in FIG. 8. The second side of the support base 51 of the modular box 50 may abut the planar portion 31 of the tray 30 to ensure that it sits securely in the defined position, which is enhanced when the indents 35 are through apertures.

Modular boxes 50 shown in FIGS. 4A-4I have different shapes and sizes support base 51 such as square and rectangle. However, different size and shape (such as circular, oval, irregular, etc.) support base 51 can also be used. Modular boxes 50 shown in FIGS. 4A-4I also have different panel heights. Depending on the size of the modular box 50, more protrusions 55 may be provided to position the modular box 50 within the internal area 33 of tray 30. Different modular boxes 50 of FIGS. 4A-4I are used to accommodate and store different sizes and shapes of cosmetic items. If the distance between adjacent indents 35 is D (as shown in FIG. 3), then the size of the support base 51 of the modular boxes 50 may be mDxnD, where m and n are whole numbers to allow adjacent modular boxes 50 to abut each other. For example, the modular box 50 shown in FIG. 5 would have a dimension of 2Dx2D.

Modular boxes 50 can be folded or collapsed into a flat planar configuration for storage within the housing 10 when not in use. Modular box 50 of FIG. 4G shows that opposing panels 52b and 52d have crease lines 54 that allow opposing panels 52a and 52c to be folded into the storage area 53 on top of the support base 51 as shown by directional arrows A. In another embodiment, modular box 50 of FIG. 4I shows that opposing panels 52a and 52c have crease lines 56 that allow opposing panels 52b and 52d to be folded into the storage area 53 on top of the support base 51 as shown by directional arrows B.

FIG. 6 shows the modular box 50 of FIG. 4A with a support base 51 having one edge connected to a panel 52b. Panels 52a, 52b, 52c and 52d are pivotably connected to each other. Along at least one edge not connected to panel 52b of the support base 51 is at least one latch 57 for engaging one or more of the remaining panels 52a, 52c and 52d to form modular box 50. When latches 57 are disengaged, the panels 52a and 52b may be folded to face panels 52d and 52c, respectively, and as shown by directional arrows C, for storage within the housing 10.

FIG. 7 shows the modular box 50 of FIG. 4A with a support base 51 having one edge connected to a panel 52b. Panels 52a and 52b are pivotably connected to each other, panels 52b and

52c are pivotably connected to each other, and panels 52c and 52d are pivotably connected to each other. Panel 52a has a latch 57 for engaging panel 52d to form modular box 50. Along at least one edge not connected to panel 52b of the support base 51 is at least one tab extension 58 for engaging corresponding cutout(s) 59 on one or more of the remaining panels, such as panel 52d, to form modular box 50. In this configuration, all the panels 52a, 52b, 52c and 52d and support base 51 can be completely unfolded for storage within the housing 10.

FIG. 12 shows the modular box 50 of FIG. 4A with a support base 51 that is removably detachable from panels 52a, 52b, 52c, and 52d. Extending from the junction between each pair of panels 52a, 52b, 52c, and 52d is a leg 60. On the first side (upper surface) of the support base 51 are four cavities 61 that are sized to frictionally and securely receive legs 60. Extending from the second side (lower surface) of the support base 51 is a plurality of protrusions 55 for positioning modular box 50 on the grid of indents 35. While panels 52a, 52b, 52c and 52d are shown to be connected to each other, they can also be individual panels that are removably connected to each other by Velcro®, friction, latch and hook, hinges, etc., as shown in FIG. 13.

The panels 52a, 52b, 52c and 52d and support base 51 can be selectively disconnected and engageable to each other with various fastening elements or configurations such as the latch 57 shown in FIG. 6 or the tab extension 58 and cutout 59 shown in FIG. 7 or the individual panels 52a, 52b, 52c and 52d shown in FIG. 13, or other configurations known to one skilled in the art, such as Velcro®, hook and slot, etc. The modular box 50 is preferably made of a light-weight, stiff material, to support its own structure and to be able to hold cosmetic items therein. For example, it can be made of cardboard or cardstock, whether laminated or not, or plastic boards. However, other material known to one skilled in the art can also be used for the modular box 50.

FIG. 9 shows a mirror 70 having an upper frame 71, a support arm 72, support wings 73 and a pedestal 74. Upper frame 71 with a reflective surface is connected to and supported by support arm 72, which is pivotably and foldably connected to and supported by pedestal 74. A pair of support wings 73 pivotably and foldably extends from each side of the support arm 72 and is removably engageable to pedestal 74, which may have slots for receiving the support wings 73. With the pivotable/foldable connection between the support arm 72 and support wings 73 and the support arm 72 and pedestal 74, mirror 70 can be collapsed to a flat planar configuration for storage within the housing 10 when not in use.

FIG. 14 shows another mirror 80 for use with the present invention. Mirror 80 has an upper reflective surface 81, a support arm 82 and a pedestal 84. Reflective mirror 81 is connected to and supported by support arm 82, which is pivotably and foldably connected to and supported by pedestal 84. With the pivotable/foldable connections between the support arm 82 and pedestal 84, and between the support arm 82 and the reflective surface 81, with the support arm 82 configured to fit between and lay flat adjacent the pedestal 84, mirror 80 can be collapsed to a flat planar configuration for storage within the housing 10 when not in use. Other foldable configurations for the mirrors 70 and 80 known to one skilled in the art can also be used. The reflective surfaces of mirror 70 and 80 may be a regular mirror or a magnified mirror or having different portions with different magnification (e.g. 3× magnification on the lower half and 5× magnification on the upper half).

One or more folded modular boxes 50 may be stored and provided within the housing 10 as part of the cosmetic orga-

nizer 100 and packaged and sold as one unit. Additional modular boxes 50 may be packaged and sold separately and independently from the cosmetic organizer 100. Modular boxes 50 and mirror 70 or 80 may be stored folded within the tray 30 or in one of the compartments 14, 15, 17a, 17b of the 5 housing 10.

To use the cosmetic organizer 100 of the present invention, a user can first remove the tray 30, folded modular boxes 50, and folded mirror 70 or 80 from the housing 10. Second, unfold or form the mirror 70 or 80 and the modular boxes 50 and set the modular boxes 50 on the tray 30. Third, remove any cosmetics items stored in the housing 10 and sort and organize them into the different modular boxes 50. The user can now easily access the cosmetics with the present invention. The reverse steps can be taken to easily transport the 15 cosmetic organizer and its contents.

The shapes of the housing 10 and tray 30 are not limited to rectangle as shown, but can be square, circle, oval, and other shapes, such as those shown in FIGS. 11A-11C.

The features of the invention illustrated and described herein are the preferred embodiments. Therefore, it is understood that the specification is intended to cover unforeseeable embodiments with insubstantial differences that are within the spirit of the specification.

What I claim is:

1. A portable modular cosmetic storage system, comprising:

a housing having a base and a cover connected to said base, said base defining a first storage compartment; at least one tray having a planar portion and a plurality of walls having a first height extending upwardly from said planar portion thereby defining an internal area, said tray having a grid of indents on said planar portion and wherein said tray is removably housed in said first storage compartment; and

at least one modular collapsible box, each modular collapsible box having a support base having a first top side and an opposing second bottom side with said first top side having a first edge and an opposing second edge; and at least first, second, third, and fourths panel pivotally interconnected to each other and to the support base, each of said panels being rectangular and having an upper edge, an opposing lower edge, a first side edge, and an opposing second side edge; wherein said panels are interconnected to each other such that said second edge of said second panel is pivotally connected to said first side edge of said first panel, said first side edge of said second panel is pivotally connected to said first side edge of said third panel, said second side edge of said third panel is pivotally connected to said second side edge of said fourth panel, and said second side edge of

said first panel is pivotally connected to said first side edge of said fourth panel, and said lower edge of said first panel is detachably connected to said first edge of said first top side of said support base, with a plurality of protrusions extending downwardly from said second bottom side of said support base so as to cooperatively engage said grid of indents of said tray when said modular collapsible box is stored in said tray;

wherein a distance between the upper edge of each of said panels, that form said modular box, and said lower edge of each of said panels, that form said modular box, define a second height greater than said first height;

wherein when said at least one modular collapsible box is in a collapsed position such that said box is in a flat planar folded configuration with said panels and said support base forming a plane, it is stored along with said tray in said housing within said first storage compartment with said housing in a closed position defined as the cover joined to the base.

2. The system of claim 1, wherein said lower edge of said third panel is pivotally connected to said second edge of said support base.

3. The system of claim 1 wherein said second side edge of said first panel and said first side edge of said fourth panel are detachably connected to each other with a fastening element.

4. The system of claim 3, wherein said fastening element is a latch on said second side edge of said first panel for removable connection with said first side edge of said fourth panel.

5. The system of claim 1, wherein each of said first, second, third, and fourth panels has at least one leg extending from said respective lower edge of each of said panels, and said first top side of said support base has a cavity for receiving each of said leg.

6. The system of claim 1 wherein said base and said cover are connected to each other with at least one zipper.

7. The system of claim 1 wherein said cover has at least one second storage compartment.

8. The system of claim 1 wherein said housing is made of a soft and flexible material.

9. The system of claim 1 wherein said tray has a handle element on at least one of said plurality of walls.

10. The system of claim 9 wherein said handle element comprises at least one opening.

11. The system of claim 9 wherein said handle element comprises at least one rolled lip extension.

12. The system of claim 1 wherein said grid of indents are evenly spaced apart.

13. The system of claim 1 wherein said grid of indents is a grid of through apertures.
